Patented June 12, 1900.

L. C. WETZEL.

COMBINED LATCH AND LOCK.

(Application filed Oct. 17, 1899.)

(No Model.)

FIG.1.

UNITED STATES PATENT OFFICE.

LEWIS CALVIN WETZEL, OF BELLEFONTE, PENNSYLVANIA.

COMBINED LATCH AND LOCK.

SPECIFICATION forming part of Letters Patent No. 651,685, dated June 12, 1900.

Application filed October 17, 1899. Serial No. 733,882. (No model.)

To all whom it may concern:

Be it known that I, LEWIS CALVIN WETZEL, of Bellefonte, in the county of Centre and State of Pennsylvania, have invented a new and Improved Combined Latch and Lock, of which the following is a full, clear, and exact description.

This invention relates to door latches and locks operated by gravity, and has for its object to provide novel, simple, and inexpensive details of construction in a device of the indicated character which adapts the slideable latch-bolt thereof to serve as a locking-bolt and which can only be operated from the outer side of the door by a suitable key.

The invention consists in the novel construction and combination of parts, as is hereinafter described, and defined in the claims.

Reference is to be had to the accompanying drawings, forming a part of this specification, in which similar characters of reference indicate corresponding parts in all the figures.

Figure 1 is a side view of the lock with one side wall of the case removed, exposing the working parts of the lock. Fig. 2 is a transverse sectional view substantially on the line 2 2 in Fig. 1. Fig. 3 is a sectional plan view taken substantially on the line 3 3 in Fig. 1. Fig. 4 is a sectional plan view substantially on the line 4 4 in Fig. 1, and Fig. 5 is a fragmentary sectional plan view taken substantially on the line 5 5 in Fig. 1.

The lock-casing 6 shown in the drawings is for a class of locks known as "mortise-locks," which in service occupy recesses formed to receive them in the free vertical edges of doors; but it is to be understood that a lock-case may be employed which is adapted for exterior attachment upon the inner side of a door, if this is desired, and in either case one side wall 6^a of the casing is made removable and securable in place by a single screw *a*. (Sectionally indicated in Fig. 1.) A face-plate 6^b is formed or secured upon one edge of the casing 6 for attachment to the free edge of the door when the lock-case is embedded in the mortise, this being a common provision for mortise-locks.

Within the casing 6 an L-shaped lever 7 is pivoted on a stud *b*, which engages the lever at or near the angular corner thereof, as shown in Fig. 1. On the limb of the L-

shaped lever 7, which projects in a nearly-horizontal plane toward the face-plate 6^b, a gravity-block 7^a is formed or secured, and 55 said block normally rests upon a projection *c*, that is an integral formation on the upper edge of the locking-bolt 8. The bolt 8 slides back and forth through the face-plate 6^b and carries a cross-pin *d*, which contacts loosely 60 with the sides of the casing 6, said pin being positioned below and nearly in vertical alignment with the projection *c* and serving to insure a correct reciprocation of the locking-bolt. 65

Two spaced lugs *e* *e'* are formed laterally on the locking-bolt 8 near its inner end, and between these lugs a keyhole *f* is formed oppositely in the side walls of the casing 6 to receive a suitably-shaped key 9 from either 70 side of the lock-case, said key by manipulation being adapted to throw the bolt 8 back or forth, as may be desired, by the contact of its bit with an appropriate lug *e* or *e'* for locking or unlocking the bolt 8. 75

Two spaced notches *g* *g'* are formed in the lower edge of the locking-bolt 8, and either of said notches will loosely receive the body of a cross-bar *h*, which is a fixture on the casing 6, and is so positioned that the notch *g* will receive it when the bolt 8 is thrown fully outward by the key 9 and the other notch *g'* will receive said cross-bar when the locking-bolt is fully retracted. 80

On the upper extremity of the upright limb 85 7^b of the L-shaped lever 7 the inner end of the latch-bolt 10 is pivoted, as at *k*, the opposite end or latching-nose 10^a thereon working loosely through the face-plate 6^b when the latch-bolt is reciprocated. 90

As shown in Figs. 1 and 3, a shoulder *i* is formed on the upper side of the latch-bolt 10 behind the latching-nose 10^a, and a like shoulder may also be provided on the lower side of said latch-bolt opposite the upper one. A 95 locking-dog 11 is pivoted in the side walls of the casing 6 above the latch-bolt 10, and on the pivot-shaft of said dog, which extends through the side wall of the lock-casing which is innermost when in place on a door, a short 100 lever 11^a is secured, which by manipulation will rock said pivot-shaft and cause the free end of the dog 11 to engage with the upper shoulder *i* or be retracted therefrom, as may

be desired. It will be seen that when the locking-dog 11 is in engagement with the shoulder *i*, as explained, the latch-bolt 10 will be locked with its nose 10^a in projected condition or 5 within a hasp-plate of ordinary construction on the casement of the door to hold the door closed.

The latch-bolt when unshackled is adapted for retraction from either side of the door by 10 the knob-spindle 12, that is represented in Figs. 1, 2, and 3, said spindle in complete form having a knob of any preferred design mounted on each end and secured thereon, as usual. On the spindle 12 within the casing 6 a cam-hub 13 is mounted, and the upright limb 7^b of the L-shaped lever 7 may be notched, as indicated in Fig. 1, to accommodate the cam-hub 13, that is positioned forward of and close to the limb 7^b, so that a depending toe 13^a on the cam-hub will have contact with the forward edge of the upright limb 7^b and by rocking movement of the cam-hub in direction of the arrow *x* in Fig. 1 rock the gravity-block 7^a upwardly and draw the 25 latch-bolt 10 inwardly, as indicated by dotted lines in Fig. 1. An arm 13^b is formed on the cam-hub 13 and is vertically disposed when the gravity-block 7^a is in a normal position or seated upon the projection *c* of the locking-bolt 8, as shown by full lines in Fig. 1.

The two normally-horizontal tumbler-fingers 14 are pivoted in the upper portion of the casing 6 side by side, their pivot-stud *m* projecting from the fixed side wall of the casing near the pivot shaft of the locking-dog 11 and loosely engaging the forward ends of the tumbler-fingers, as shown in Figs. 1 and 2. The free portions 14^a of the tumbler-fingers 14 are notched in their lower edges at a 35 point directly above the upright arm 13^b and receive the upper end of said arm when the latch-bolt 10 is projected, said arm 13^b passing freely up behind the body of the latch-bolt, so as to enable it to have a locked engagement with the gravity-actuated bodies of 40 the tumbler-fingers, as shown by full lines in 45 Fig. 1.

The lower edges of the two tumbler-fingers 14 are cut away toward their free ends 14^a to 50 afford clearance for a keyhole *n*, that extends oppositely through each side wall of the casing 6 for admission of a proper key (not shown) from the exterior of the door to engage the bit thereof with the tumbler-fingers 55 for their upward rocking movement and consequent release of the upright arm 13^b. Below the tumbler-finger 14 and above the slideable latch-bolt 10 a tripping-arm 15 is held to rock by the transversely-disposed rock-shaft 60 16, held loosely in perforations of the sides of the casing 6, said shaft being adapted for rocking movement by the thumb-piece 17, fixed upon the end of said shaft exterior of the casing, as shown in Figs. 2 and 3. On 65 the end of the tripping-arm 15, which is shortest, a cam-head 15^a is provided, which, if turned toward the lower edges of the tum-

bler-fingers 14, will raise them sufficiently to release their notched portions from engagement with the upper end of the upright arm 7^b, as shown by dotted lines in Fig. 1.

When the cam-head 15^a is rocked to lift the tumbler-fingers 14, the longer and thinner portion of the tripping-arm 15 will pass behind the body of the latch-bolt 10 and at the free end thereof impinge upon the forward edge of the upright arm 13^b, so as to rock it away from the notches in the tumbler-fingers 14 simultaneously with the release of said arm from engagement with the notches, as indicated by dotted lines in Fig. 1.

In some constructions of the lock it may be preferred to dispense with knobs on the spindle 12 and simply journal it in the sides of the casing 6. If this is done, the thumb-piece 17 85 may be used to retract the latch-bolt on one side of the door, and a key inserted in the key-hole *n* in the opposite side of the lock-case 90 may be employed for drawing the latch-bolt away from a hasp-plate, with which it may be engaged.

If preferred, a keyhole *o* may be formed oppositely in the side walls of the casing adjacent to a guard 18, which is positioned below and near the horizontal limb of the L-shaped lever 7, so that the introduction of a suitable key into the keyhole *o* will permit of the upward rocking movement of the weighted limb of the L-shaped lever 7 and a retraction of the latch-bolt 10 in an obvious manner. 100

Referring again to the locking-bolt 8, it will be seen that the bit of the key 9 must be exactly proportioned in length to suit the spaced interval between the lugs *e e'* on the inner end of the locking-bolt, as in case said bit is not of sufficient length the rear end of the locking-bolt will not be raised up far enough to clear the bar *h* from the walls of the notch *g* it occupies when the nose of the locking-bolt is projected from the lock-case, 110 and the bolt cannot be retracted by a key that is not correct in form nor can the bolt be thrown to lock it.

It will be seen that if the L-shaped lever 7 is in normal adjustment, which adapts the 115 gravity-block 7^a to rest upon the projection *c*, this will not impede the operation of locking or unlocking the bolt 8 unless the locking-dog 11 is adjusted to engage its nose with the shoulder *i* on the latch-bolt 10. In this 120 case the retention of the latch-bolt 10 in projected adjustment will prevent the upward rocking movement of the gravity-block 7^a on the lever 7, and as said block rests upon the locking-bolt 8 while the latter is thrown to 125 lock it evidently both the latch-bolt and locking-bolt will be held from retraction by the locked adjustment of the dog 11.

It will be evident from the foregoing description that a cheap, strong, and reliable 130 latch and lock is afforded, which is very secure and that is available for use generally, being adapted for application to doors guarding exits from a building or upon doors be-

tween communicating rooms of a dwelling-house.

From the peculiar construction of the device the latch-bolt 7 may be turned over so that the sloped face of its nosepiece 7^a may be changed to face in an opposite direction and the lock be thus adapted for application to doors that swing in opposite directions, and the lock is also well adapted for use on either right-hand or left-hand swinging doors.

Having thus described my invention, I claim as new and desire to secure by Letters Patent—

1. In a lock, the combination with a casing, an L-shaped lever pivoted in the casing, a gravity-block on the lower horizontal limb of the L-shaped lever and a slidable latch-bolt pivoted by its inner end on the upper end of the upright limb of the L-shaped lever, of a knob-spindle rockable in the casing, a cam-hub having a toe adapted to rock the L-shaped lever and retract the latch-bolt, an upright arm on the cam-hub, two horizontal tumbler-fingers notched to engage and lock the upright arm and thus prevent rocking of the knob-spindle, and means substantially as described for release of the tumbler-fingers from the upright arm.

2. In a lock, the combination with a casing an L-shaped lever pivoted at its corner therein, having a gravity-block on its lower horizontal limb, and a slidable latch-bolt pivoted at its inner end on the upper end of the L-shaped lever, of a knob-spindle rockable in the casing, a cam-hub on said spindle having a toe adapted to rock the L-shaped lever and retract the latch-bolt, an upright arm on the cam-hub, one or more horizontal tumbler-fingers pivoted by one end upon the casing, and notched on the lower edge, to engage the upper end of said arm to lock the latch-bolt from retraction, and means such as a keyhole in the casing and a suitable key, whereby the tumbler-finger may be disengaged from the upright arm of the cam-bolt, and the latch-bolt released.

3. In a lock, the combination with a casing, a slidable latch-bolt therein, an L-shaped lever pivoted in the casing at its angle, and having its lower limb weighted, the upright limb of said lever being pivoted upon the inner end of the latch-bolt, of a knob-spindle rockable in the casing, a cam-hub thereon

having a toe engaging the upright limb of the L-shaped lever, and two pivoted tumbler-fingers operative by a key, and notched to engage with the upper end of the upright arm on the cam-hub, thereby holding the knob-spindle from rotation, and means such as a key, adapted to rock the weighted limb of the L-shaped lever upwardly and thereby retract the latch-bolt.

4. The combination with a casing, a slidable latch-bolt therein, a rockable L-shaped lever weighted in its lower limb and pivoted by its upper limb upon the inner end of the latch-bolt, a rockable knob-spindle, a cam-hub thereon having a toe pressing the upright limb of the L-shaped lever, an arm on the cam-hub projecting upwardly, and two pivoted horizontal tumbler-fingers, notched in their lower edges to receive the upper end of the upright limb and thus prevent rotation of the knob-spindle, of a tripping-arm held to rock in the casing below the tumbler-fingers, a thumb-piece on the outer end of the shaft carrying the tripping-arm, which arm is adapted to lift the tumbler-fingers by one of its ends, and rock the upright arm of the cam-hub with its remaining member, so as to release the knob-spindle.

5. The combination with a casing, an L-shaped lever pivoted in the casing at its angular corner, so that one weighted limb is nearly horizontal and the other limb upright therein, a latch-bolt slidable through an end wall of the casing having its inner end pivoted upon said upright limb, a knob-spindle, a cam-hub thereon, which when rocked, will draw the latch-bolt, an upright arm on said limb, and means to lock said arm from rocking releasable with a key, of a locking-bolt whereon the weighted limb of the L-shaped lever rests when the latch-bolt is slid outwardly, said bolt having two spaced notches in its lower edge, a fixed cross-bar on the casing which will enter either notch to hold the locking-bolt projected or retracted, a keyhole and a key that may be entered in said key-hole, and by manipulation raise and slide the locking-bolt when the latch-bolt is free to slide.

LEWIS CALVIN WETZEL.
